UNITED STATES PATENT OFFICE.

WILLIAM H. SAART, OF ATTLEBOROUGH, MASSACHUSETTS, ASSIGNOR TO
THE JAMES E. BLAKE COMPANY, OF SAME PLACE.

DESIGN FOR A HANDLE FOR BUTTON-HOOKS OR SIMILAR ARTICLES.

SPECIFICATION forming part of Design No. 31,225, dated July 18, 1899.

Application filed June 22, 1899. Serial No. 721,491. Term of patent 3½ years.

To all whom it may concern:

Be it known that I, WILLIAM H. SAART, of Attleborough, in the county of Bristol and State of Massachusetts, have invented and produced a new and original Design for the Handle of a Button-Hook or Similar Article, of which the following is a specification, reference being had to the accompanying drawings, forming part thereof.

Figure 1 is a side view of a handle, showing my design connected to a button-hook, the blade of a paper-cutter being indicated in broken lines. Fig. 2 is a section of the handle on the line A A of Fig. 1.

The leading feature of my design consists in the convex circular panels inclosed in raised foliated scrolls extending along the curved margin of the handle, as will be more fully described hereinafter.

In the drawings, A indicates the button-hook, B the stem, and C the blade of the handle. From the ferrule *a* extends the honeysuckle ornament *b*, supported on each side by the scrolls of the marginal beads *c*, the space between which is filled with the graduated raised beads *d*. The outwardly and inwardly curved margin of the handle gradually expands in width and is ornamented on each side by the raised and foliated scrolls *e*,

inclosing the convex circular panel *f*. From 30 the scrolls *e* extend the foliated branches *g* along the margin of the handle, inclosing the pendent floral ornament *h*. The convex panel *i* is inclosed by the raised foliated scrolls *k*, the leaves of which extend partially over 35 scalloped segmental shells, the radial lines of which give to the convex panel *i* a globular appearance. The leaves of the raised foliated scrolls *k* extend upward and terminate in the scrolls *l* on each side of the central crest ornament *m*, from which a number of graduated beads extend downward.

To the eye the handle presents the appearance of a small and a large globular figure supported and inclosed in the ornamental 45 portions of the handle.

Having thus described my invention, what I claim as new, and desire to secure by Letters Patent, is—

The design for the handle of a button-hook 50 or similar article substantially as herein shown and described.

In witness whereof I have hereunto set my hand.

WILLIAM H. SAART.
